UNITED STATES PATENT OFFICE.

WILLIAM M. KELLY, OF JERSEY CITY, NEW JERSEY.

PRINTING PRESS.

Application filed August 6, 1921. Serial No. 490,290.

The present invention relates to printing presses and more particularly the two revolution type.

The principal objects of the invention are 5 to provide:

1. An improved mechanism for reciprocating the bed of the press.
2. Means connecting the air cylinders for cushioning the bed at the ends of its stroke 10 constructed and arranged so that the compression thereof may be relieved when starting up the press.
3. To provide means for positively reciprocating the antifriction rolls or sliders supporting the bed of the press in accordance 15 with the reciprocation of the bed.

Other objects and features of novelty will be apparent from the description taken in connection with the drawings, in which

20 Figure 1 is a side elevation of a press constructed in accordance with the present invention;

Figure 2 is a side elevation of the opposite side of the press;

25 Figure 3 is a top plan view of the base or frame, the bed and parts above the same being removed;

Figure 4 is a sectional elevation of the base and bed taken substantially on the 30 line 5—5 of Fig. 3;

Figure 5 is a sectional elevation of the base and bed taken substantially on the line 6—6 of Fig. 3;

Figure 6 is a sectional elevation of the 35 base, bed, cylinder and inking mechanism taken substantially on the line 7—7 of Fig. 3;

Figure 7 is a diagrammatic view illustrating the piping connecting the air cylinders;

40 Figure 8 is a diagrammatic view of the mechanism for reciprocating the bed and showing the gears for driving the ink rolls and also the means for rotating the cylinder.

Referring to the drawings, in which the 45 same reference character refers to like parts, it will be seen that the entire press is driven from a motor 30 disposed at the feeder end thereof. This motor is rotatively connected to a transverse shaft 31 at the other or delivery end of the press by means of a relatively long belt drive 32, this belt passing over a pulley 33 on the armature shaft of the motor and a pulley 34 on the transverse shaft 31. The shaft 31 is carried by the side members 35 and 36 of the base or frame 50 and has secured thereto a pinion 37 disposed adjacent the side member 36 and mesh-

ing with a gear 38 non-rotatively secured to a short shaft 39 extending through the said side frame 36. Outside the side member 36 the shaft 39 carries a pinion 40 in mesh with a large gear 41 keyed to a transverse shaft 42. This large gear meshes with a like large gear 43 in turn keyed to a transverse shaft 44 and also meshing with a smaller gear 45 keyed to a short transverse shaft 46 which 60 within the base carries a crank arm 47 having a crank pin 48.

It is an object of the invention to provide a simple and positive means for reciprocating the bed of the press at a uniform velocity 70 during the greater portion of its stroke and to give an easy and smooth reversal at the end portions of the reciprocation. For these purposes the mechanism comprises in combination with the reciprocating bed, 75 gearing for driving the bed during the uniform velocity portion of its stroke and a second reciprocating member driven in timed relation with the bed to make a plurality of reciprocations while the bed makes a 80 single reciprocation and means for connecting the bed and member when the latter is making one of its reversals whereby the bed is quickly reversed thereby. To these ends the mechanism comprises a pair of segmental 85 gears 49 and 50 subtending angles of about 120° and disposed between the large gears 41 and 43 and the side member 36. Preferably these segmental gears are removably attached to the large gears 41 and 43 as by 90 means of bolts 51. These segmental gears are adapted to alternately mesh with a pinion 52 on a transverse shaft 53 which has a gear 54 secured thereto continually in mesh with a centrally disposed rack 55 on the bottom of the bed 56. The bed reciprocates on four parallel ways 57 carried on cross members 58 connected to the side members of the base. In order to eliminate friction four 95 groups of rollers 59 are interposed between the bed and the ways 57 and these rollers are held in proper spaced relation lengthwise of the bed by side bars 60.

One of the objects of the invention is to 105 positively reciprocate each of these groups of rollers in timed relation with the reciprocations of the bed to thereby reduce the power required to reciprocate the bed and make the whole mechanism more positive and accurate. To this end the adjacent side 110 members 60 of one pair of rollers is connected by a cross-member 61 and the other

pair by the cross-member 62. The cross-member 61 has connected thereto a rack 63 slidable in the way 64 and the cross-member 62 has a similar rack 65 connected thereto 5 slidable in the way 66. These racks 63 and 65 mesh respectively with gears 67 and 68 secured to the shaft 53, the said gears being half the diameter of the bed driving gear 54. In this manner the groups of rollers will be 10 reciprocated so that the peripheral velocities thereof will be identical with the velocity of the bed.

The bed is driven during the uniform velocity portions of its reciprocations by the 15 gear 54. For the purpose of reversing the bed at the ends of its stroke a reciprocating member or frame 69 is slidably carried within the base of the press and at one end thereof has a slot 70 slidably receiving the block 20 71 on the crank pin 48. Preferably the diameter of the crank pin circle is the same as the pitch diameter of the gear 45 and this is one-third of the pitch diameter of the gears 41 and 43. This member or frame 69 25 is thus reciprocated by means of the crank 47 and associated parts and is adapted to be periodically connected with the bed when the latter is making a reversal. The frame 69 is 30 slidably supported in bearings 72 and 73. Adjacent the ends of the upper edge of the frame 69 are the short rack blocks 74 and 35 75 which at the proper times are adapted to be alternately moved into mesh with the rack 55 on the bottom of the bed so that the two reciprocating parts are connected 40 for movement in unison. The rack block 74 is carried by an arm 76 which is pivoted at 77 to frame 69 and has a laterally extending pin 78 which works in a cam groove 79 45 formed in the cam block 80 carried by the frame of the press. In a similar manner the rack block 75 is carried by an arm 81 pivoted at 82 to the frame 69 and has a laterally extending pin 83 working in the cam groove 84 carried by the cam block 85 secured to 50 the frame of the press. The cam grooves 79 and 84 are formed and positioned so that the rack blocks will be alternately moved into mesh with the bed rack 55 during the reversal of the bed.

For the purpose of describing the operation of the bed reciprocating mechanism it will be noted in Fig. 5 that the bed is at the left hand end of its stroke and the short 55 rack 74 is in mesh with the bed rack 55, the bed being driven from the crank pin 48. The crank is moving in a counter-clockwise direction as viewed in Fig. 6 and when it reaches its lowermost position has brought 60 the bed up to the same velocity as the peripheral velocity of gear 54 when driven by one of the segmental gears 49 or 50 and when the crank reaches this position the rack block 74 begins to withdraw from engagement 65 with the rack 55. At the same time the

segmental gear 50 comes into mesh with the gear 52 thereby rotating shaft 53 and through gear 54 driving the bed. While the segmental gear 50 is thus driving the bed the crank pin 48 will make one complete 70 revolution and at the end of this revolution the rack block 75 will be moved into mesh with the bed rack 55 so that the bed will be reversed at the right hand end of its stroke 75 as viewed in Fig. 5 while the crank is moving through the right hand half of its rotation. When the crank reaches its uppermost position as viewed in Fig. 5 the bed will have started back in its motion toward the left 80 as viewed in Fig. 5 and the rack bar will begin to be moved out of engagement with the bed rack and the segmental gear 49 will just have come into mesh with the pinion 52, thus driving the bed by means of the segmental gear 49 at a uniform velocity. At 85 the point when the said segmental gear 49 is about to leave the pinion 52 the rack block 74 will be moved into engagement with the bed rack for reversing the bed at the other end of its stroke. The above described cycle 90 of operation is repeated during each complete reciprocation of the bed.

It will be noted in the above described mechanism for reciprocating the bed, the bed driving gear 54 and the rack blocks 74 and 95 75 cooperate with the single rack 55 secured to the bed. Furthermore, by making the segmental gears of smaller diameter than the large intermeshing gears 41 and 43 it is possible to have these latter gears of relatively 100 great diameter even with a comparatively low bed.

Referring now to Fig. 7, the bed at the ends of its reciprocations is cushioned by pistons 86 secured to the bed and entering 105 the cylinders 87 having flap valves 88, in a well known manner. The compression effect in these cylinders is so great that in starting up the press the motor has not sufficient power to reverse the bed. Means is therefore provided for relieving this compression. In the embodiment of the invention illustrated this is accomplished by connecting the closed ends of the cylinders. Thus as shown 110 the pipes 89 connected with the closed ends 115 of the cylinders are in communication through a stop cock or valve 90. At each side of this valve 90 is an adjustable relief valve 91. In normal operation of the press the valve 90 is closed cutting off communication between the pipes 89 the compression in the cylinders being slightly relieved through the relief valves 91. In starting up the press however the valve 90 is turned so as to place 120 the pipes 89 in communication whereupon air compressed in one pair of cylinders will be conveyed through the pipes 89 and exhausted through the other pair. In this manner the compression is so relieved that 125 the press may be started up.

The following applications have been divided out of this case:

Serial No.	Filing date.	Title.
36,942	June 13, 1925	Front guide (Patented Jan. 18, 1927, No. 1,615,174)
36,943	June 13, 1925	Machine element
42,086	July 7, 1925	Printing press
42,087	July 7, 1925	Printing press
10 184,116	April 15, 1927	Sheet feeders
184,122	April 15, 1927	Sheet feeding mechanism

The following application is a continuation in part of this case:

Serial No.	Filing date.	Title.
34,687	June 3, 1925	Extension sheet delivery

The following application is directed to pile elevating mechanism for this press and refers to this case:

Serial No.	Filing date.	Title.
490,289	August 6, 1921	Pile elevating mechanism

The following applications respectively show mechanisms suitable for use with this press:

Serial No.	Filing date.	Title.
30 184,117	April 15, 1927	Sheet feeding mechanism
490,291	August 6, 1921	Printing press (Patented Oct. 2, 1923, No. 1,469,515)

Having described the invention what is claimed as new and desired to be secured by Letters Patent is:

1. A printing press bed movement including in combination, a reciprocating bed having a centrally disposed longitudinal rack, a pinion continually meshing with said rack, means rotating said pinion at a constant speed in opposite directions at regular intervals to drive the bed at a uniform velocity, and means periodically engaging said rack during the end portions of the stroke of the bed to reverse the same.

2. A printing press bed movement including in combination, a reciprocating bed having a centrally disposed longitudinal rack, a pinion continually meshing with said rack, means rotating said pinion at a constant speed in opposite directions at regular intervals to drive the bed at a uniform velocity, reciprocating rack blocks at opposite ends of said bed having a shorter stroke than the bed, and means to alternately move said blocks into engagement with said rack during the end portions of the bed stroke to reverse the bed.

3. A printing press bed movement including in combination, a reciprocating bed having a centrally disposed longitudinal rack, a reciprocating member having a shorter stroke than the bed, a pinion continually in mesh with said rack, means to rotate said

pinion at a constant speed in opposite directions at regular intervals to drive the bed during the constant velocity part of its stroke, and means to connect said bed and member during the end portions of the stroke of the bed to reverse the same including rack blocks adapted to mesh with said rack, and means to actuate said blocks into and out of engagement with said rack.

4. A printing press bed movement including in combination, a reciprocating bed having a centrally disposed longitudinal rack, a pinion continually in mesh with said rack, a second pinion coaxial with said first pinion, a pair of large meshing gears, means to drive one of said gears at a constant speed, a smaller diameter segmental gear coaxial with each large gear, said segmental gears adapted to alternately mesh with said second pinion to drive the same in opposite directions at regular intervals, and means cooperating with said rack to reverse the bed.

5. A printing press bed movement including in combination, a reciprocating bed having a centrally disposed longitudinal rack, a pinion continually in mesh with said rack, a second pinion coaxial with said first pinion, a pair of large meshing gears, means to drive one of said gears at a constant speed, a smaller diameter segmental gear removably secured to each large gear, said segmental gears adapted to alternately mesh with said second pinion to drive the same in opposite directions at regular intervals, and means cooperating with said rack to reverse the bed.

6. In a printing press, in combination, a base frame having two side members, a bed reciprocable on said frame, and having a centrally disposed longitudinal rack, a transverse shaft carried by said members having a pinion continually in mesh with said rack, a second pinion on said shaft on the outer side of one of said members, a pair of large meshing gears on the same side of said member, means to drive said gears at a constant speed, a segmental gear secured to each large gear between the large gear and member and adapted to alternately mesh with and drive the second pinion in opposite directions at regular intervals, and means cooperating with said rack to reverse the bed at the ends of its stroke.

7. In a printing press, in combination, a base, a bed reciprocable on said base, rollers supporting the bed on the base, a rack on the bed, a shaft, a gear on the shaft meshing with the rack to reciprocate the bed, a second gear on the shaft half the diameter of the first gear, a reciprocable rack meshing with said second gear, and means connecting the last mentioned rack and rollers to reciprocate the latter with the rack.

In testimony whereof I hereunto affix my signature.

WILLIAM M. KELLY.
